US00D720720S

(12) **United States Design Patent**
Yu

(10) **Patent No.:** **US D720,720 S**
(45) **Date of Patent:** **** Jan. 6, 2015**

(54) **EARPHONE**

(71) Applicant: **Shenzhen Rapoo Technology Co., Ltd.**
Shenzhen, Guangdong (CN)

(72) Inventor: **Cuijing Yu**, Guangdong (CN)

(73) Assignee: **Shenzhen Rapoo Technology Co., Ltd.**
Shenzhen (CN)

(**) Term: **14 Years**

(21) Appl. No.: **29/472,597**

(22) Filed: **Nov. 14, 2013**

(30) **Foreign Application Priority Data**

May 15, 2013 (CN) 2013 3 0178985

(51) **LOC (10) Cl.** **14-01**
(52) **U.S. Cl.**
USPC **D14/205**

(58) **Field of Classification Search**
CPC H04R 25/00; H04R 1/1066; H04S 1/005
USPC D14/205; D29/112; 181/129, 130, 135;
379/430, 431; 381/380, 381, 370, 374,
381/382; 2/209; 455/90.3, 575.1

See application file for complete search history.

Primary Examiner — Paula Greene

(57) **CLAIM**

The ornamental design for an earphone, as shown and described.

DESCRIPTION

FIG. 1 is a front view of an earphone of my new design;
FIG. 2 is a back view of the earphone of FIG. 1;
FIG. 3 is a left view of the earphone of FIG. 1;
FIG. 4 is a right view of the earphone of FIG. 1;
FIG. 5 is a top view of the earphone of FIG. 1;
FIG. 6 is a bottom view of the earphone of FIG. 1;
FIG. 7 is a left perspective view of the earphone of FIG. 1;
FIG. 8 is a right perspective view of the earphone of FIG. 1;
FIG. 9 is a top perspective view of the earphone of FIG. 1;
and,
FIG. 10 is a bottom perspective view of the earphone of FIG. 1.

1 Claim, 10 Drawing Sheets
